S. WHEATLEY & C. B. LARMON,
SPARKING DEVICE.
APPLICATION FILED FEB. 3, 1913.

1,088,388.

Patented Feb. 24, 1914.

UNITED STATES PATENT OFFICE.

SAMUEL WHEATLEY AND CHARLES B. LARMON, OF KANSAS CITY, MISSOURI,
ASSIGNORS, BY MESNE ASSIGNMENTS, TO VICTOR ACETYLENE SUPPLY
COMPANY.

SPARKING DEVICE.

1,088,388.

Specification of Letters Patent. Patented Feb. 24, 1914.

Application filed February 3, 1913. Serial No. 745,897.

To all whom it may concern:

Be it known that we, SAMUEL WHEATLEY and CHARLES B. LARMON, citizens of Great Britain and the United States, respectively, 5 residing at Kansas City, in the county of Jackson and State of Missouri, have invented certain new and useful Improvements in Sparking Devices, of which the following is a specification.

10 Our invention relates to improvements in gas igniters whereby a spark, for the ignition of gas, is produced by impingement of a pyrophoric element against a scraper.

One object is to produce a simple and efficient device of this character wherein the 15 sparking elements automatically and instantly return to normal position away from the flame after ignition of the gas, thereby avoiding injury to parts which would result 20 from exposing them to said flame.

A further object is to prolong the life of the sparking elements by keeping them out of contact with each other throughout their forward stroke and part of their rearward 25 stroke, so that there will be no wear until they impinge against each other to produce a spark.

Other objects of the invention will hereinafter appear, and in order that said invention may be fully understood, reference 30 will now be made to the accompanying drawing, in which:

Figure 1 is a side elevation of a burner provided with our igniting device, the several parts being in position to be actuated 35 to produce a spark. Fig. 2, is a side elevation, looking from the same side as Fig. 1, but with the parts in the position they occupy after producing a spark. Fig. 3 shows 40 the reverse side of the sparker to that disclosed by Fig. 1, with the burner removed. Fig. 4 shows the position of the parts just before producing a spark. Fig. 5 is an enlarged irregular section on line V—V of 45 Fig. 2. Fig. 6 is a section, enlarged, of certain parts of the invention.

The type disclosed is especially applicable to acetylene gas burners, but of course, use of the device is not limited to that particular type of burner.

1 designates the burner provided at its upper end with a tip 2 to which the flow of gas is controlled by a conical valve 3, ex-

tending transversely through the burner, as shown on Fig. 5. 55

4 designates a hand-controlled lever mounted upon the valve stem 5, where it is reliably secured by a spring washer 6 and a screw 7. Lever 4 is provided with a flat spring 8 having a detent 9 at its free end. Said detent projects through an opening 10 in lever 4 and extends into the path of a lever 11. Lever 4 has a lug 9^a to contact therewith in providing a broad bearing surface for detent 9. The hand-controlled 65 lever 4 is provided at its pivoted end with lugs 12 and 13, adapted to alternately impinge against a stud 14, projecting from the adjacent side of burner 1, thus limiting the rotary movement of valve 3 and lever 4. 70 Lever 11 is fulcrumed upon a screw 15, engaging the upper portion of burner 1, and has a curved lower portion 11^a beveled on the side adjacent detent 9, as shown on Fig. 6, so that said detent may be guided by said 75 beveled side to the upper edge of lever 11.

16 designates a holder in the form of a bell-crank lever, pivotally-secured by a pin 17 to the long end of lever 11, which end has a lug 18 extending laterally beneath the 80 upper arm of holder 16, to limit the downward pivotal movement of said arm, which is normally held in contact with lug 18 by the weighted arm 16^b of holder 16. Holder 16 is provided at its upper arm with a sparking element 19, adapted to coact with a steel 85 file or other sparking element 20 to produce a spark.

File 20 may be slightly curved as shown on Fig. 1, or straight as shown on Fig. 4, 90 and is fixed to the upper end of an arm 21 fulcrumed beside lever 11 upon screw 15. Arm 21 is provided at its pivoted end with extensions 22 and 23, adapted to alternately contact with the valve-stem 5 and thus limit 95 pivotal movement of said arm.

24 designates a spring which is primarily actuated by the hand-controlled lever 4 and in a measure controls said hand-lever 4, the lever 11, and the arm 21, as will hereinafter 100 appear. Spring 24 has a coiled intermediate portion 25, secured to arm 21 by a pin 26. The lower end of spring 24 extends through an eye 27 integral with the pivoted portion 105 of the hand-controlled lever 4, and the upper end of said spring bears against a lug 28,

extending laterally from the long end of lever 11 and overlapping the adjacent portion of arm 21.

29 designates a rod depending from the free end of lever 4 to within convenient reach of an operator.

When it is desired to ignite the gas, lever 4 is drawn downward by rod 29, until checked by lug 12 impinging against stud

10 14. As lever 4 moves downward, detent 9 engages the curved portion 11^a of lever 11, and draws said portion downward on its initial stroke until detent 9 slips off the extreme end thereof, which however, does not occur until just after holder 16 and its 15 sparking element 19 have been raised to the position shown on Fig. 4. As the long end of lever 11 swings upward, it, through lug 28, carries the upper end of spring 24 therewith, which, through its connection with arm 21, carries said arm therewith until its extension 23 contacts the valve-stem 5, after which lever 11 continues on its upward movement alone, thereby moving the 20 25 sparking elements 19 some distance in advance of the file 20. The continued movement of lever 11 after arm 21 has been arrested, tensions spring 24, hence when detent 9 swings clear of the curved terminal

30 11^a, said spring instantly retracts lever 11 and causes it to sweep backward at great speed. As holder 16 is carried backward with lever 11, the inertia of the weight arm 16^b, causes the sparking element 19 to swing 35 upward into contact with the file 20, thus producing a spark which ignites the gas that has been turned on by the downward movement of the hand-controlled lever 4. As lever 11 swing backward lug 28 contacts 40 arm 21 and carries the same backward therewith to the position shown on Fig. 2, where further backward movement is limited by extension 22 contacting the valve-stem 5.

The parts are reliably held in the position 45 shown on Fig. 2, by the spring 24, and, consequently, the sparking elements are held away from the flame while the valve 3 will be held in open position by the pressure of spring 24 upon ear 27, which pressure holds 50 lug 12 against stud 14.

When it is desired to cut off the gas, lever 4 is raised until lug 13 contacts stud 14 (Fig. 1), where it is held by spring 24.

As the sparking elements do not engage 55 each other except at the time of impact when producing a spark, wear thereby is reduced to a minimum.

Having thus described our invention, what we claim and desire to secure by Letters 60 Patent, is:

1. In a device of the character described, a pivoted arm, a sparking element carried thereby, a lever for actuating said arm, a second sparking element operably-mounted

upon said lever and arranged to strike 65 against the first sparking element, a second lever mounted adjacent the first lever, and a detent on said second lever whereby the same actuates the first lever.

2. In combination with a gas burner, a 70 sparking attachment consisting of a sparking element, an arm pivotally secured to the burner and carrying said sparking element, a lever also pivotally secured to the burner for actuating said arm, a second 75 sparking element operably-mounted upon said lever and arranged to strike against the first sparking element, a second lever mounted adjacent the first lever to actuate the same, means on the burner and the second 80 lever to limit the movement of the latter, and resilient means for holding said second lever in contact with its movement limiting means.

3. In combination with a gas burner, a 85 sparking attachment therefor consisting of a sparking element, an arm pivoted to said burner and carrying said sparking element, a lever also pivoted to the burner and arranged to actuate said arm, a second spark- 90 ing element operably-connected to said lever and arranged to strike against the first sparking element, coacting means on the burner and the arm for checking the same before said lever has completed its 95 initial stroke, a second lever mounted upon the burner valve and arranged to impart the initial stroke to the first lever and then release the same, coacting means on the burner and said second lever to check the 100 movement of the latter after the same has opened or closed the burner valve, and resilient means mounted upon the arm and engaging the levers whereby speedy retraction of the first lever and its sparking element 105 is accomplished when released by the second lever, and whereby the second lever is reliably held at the end of either its initial or following stroke.

4. In a device of the character described, 110 a pivoted arm carrying said sparking element, a lever for actuating said arm, a holder pivotally-secured to said lever, a second sparking element carried by said holder and arranged to strike against 115 the first sparking element, a weighted arm on the holder to throw the second sparking element in position to strike the first sparking element, means for moving said lever on its forward stroke, means for checking the 120 arm before said lever has completed its forward stroke, and resilient means connecting the arm and the means for moving the lever on its forward stroke, said resilient means bearing on the lever to speedily retract the 125 same and cause the second sparking element to contact the first one.

5. In a device of the character described,

a sparking element, a pivoted arm carrying said sparking element, a lever for actuating said arm, a second sparking element operably-connected to said lever and arranged to 5 strike against the first-mentioned sparking-element, means for checking the arm before said lever has completed its initial stroke, a second lever arranged to impart the initial stroke to the first-mentioned lever and then 10 release the same, and resilient means connecting the arm and said second lever and bearing against the first mentioned lever whereby speedy retraction of the latter and its sparking element is accomplished when 15 released by the second-mentioned lever.

6. In a device of the character described, a pivoted arm carrying a sparking element, a lever for actuating said arm, said lever having a beveled terminal, a second sparking element operably-connected to the lever and arranged to strike against the first-mentioned sparking-element, means for checking the arm before said lever has completed its initial stroke, a 25 second lever arranged to impart the initial stroke to the first-mentioned lever and then release the same, a catch on the second lever adapted to slip over the beveled terminal of the first lever and positively engage the latter to impart the initial stroke thereto, and resilient means connecting the arm and said second lever and bearing against the first lever whereby speedy retraction of the latter and its sparking element is accomplished 30 when released by the second lever.

7. In combination with a gas burner, a pivoted arm carrying a sparking element, an arm pivoted to said burner and carrying said sparking element, a lever also pivoted to the burner and arranged to actuate said arm, a second sparking element operably-connected to said lever and arranged to strike against the first 40 sparking element, coacting means on the burner and the arm for checking the same before said lever has completed its initial stroke, a second lever mounted upon the burner valve and arranged to impart the initial stroke to the first lever and then re-

lease the same, and resilient means connecting the arm and said second lever and bearing against the first lever whereby speedy retraction of the latter and its sparking element is accomplished. 50

8. In a device of the character described, a pivoted arm carrying a sparking element, a lever pivotally-mounted beside said arm to actuate the same, a second sparking element operably-connected to said lever and arranged to strike 55 against the first-mentioned sparking element, means for moving said lever on its initial stroke, a lug on the lever adapted to engage and restore the arm to normal position after said lever has completed its initial stroke, 60 means for checking the arm before said lever has completed its initial stroke, and resilient means connecting the arm and the means for moving the lever on its initial stroke, said resilient means bearing against the lug 65 of the lever whereby speedy retraction of the latter and its sparking element is accomplished. 70

9. In a device of the character described, a pivoted arm, a sparking element carried 75 by said arm, a lever for actuating said arm, said lever having a lug normally bearing against said pivoted arm, a holder pivoted to said lever, a sparking element carried by said holder and arranged to strike against 80 the first sparking element, a second lever mounted adjacent the first lever, a detent extending through the second lever and adapted to engage the first lever to actuate the same, a spring for pressing said detent 85 toward the first lever, and resilient means mounted upon the pivoted arm and bearing against the lug on the first lever whereby the sparking element carried by the holder is caused to quickly strike the companion 90 sparking element.

In testimony whereof we affix our signatures in the presence of two witnesses.
